UNITED STATES PATENT OFFICE.

BENJAMIN WEXLER, OF BROOKLYN, NEW YORK, ASSIGNOR TO THE PEELLE COMPANY,
OF BROOKLYN, NEW YORK, A CORPORATION OF NEW YORK.

BEARING MEMBER FOR IRON DOORS.

1,237,430.

Specification of Letters Patent. Patented Aug. 21, 1917.

Application filed December 9, 1915. Serial No. 66,008.

To all whom it may concern:

Be it known that I, BENJAMIN WEXLER, a citizen of the United States, and a resident of New York city, borough of Brooklyn, in the county of Kings and State of New York, have invented certain new and useful Improvements in Bearing Members for Iron Doors, of which the following is a specification.

10 This invention relates to improvements in bearing members for iron doors, and particularly to bearing members formed of parts of the iron door frames at the side edges.

15 The object of my invention is to provide such bearing members formed out of part of the frame of the door and projecting beyond said frame, which bearing members are held against movement toward the door proper and against movement transversely to their length, thereby preventing accidental displacement transversely to the length of the bearing members, and also preventing the bearing members from being

25 pushed back toward the edge of the door, but at the same time permitting such bearing members to yield to the effects of heat, when the door is subjected to fire or great heat, or the parts of the same become heated,

30 all of which is very simple in construction, strong, durable and reliable and effective in action.

In the accompanying drawings in which like letters of reference indicate like parts in all the figures:

35 Figure 1 is a face view of a door, parts being broken away, provided with my new and improved bearing member and a bar against which the bearing member can rest, 40 and which bar forms a guide on which the bearing member can run up and down while guiding the door in its vertical movements.

Fig. 2 is an enlarged view of the bearing members.

45 Fig. 3 is a horizontal sectional view on the line $x-x$ of Fig. 1.

The door 1 which is to be mounted to slide vertically at a guide bar 2, is constructed with a frame 3 made of channel bars, 50 angle bars or T-irons, the T-iron construction being preferred and to the said T-iron frame a corrugated iron filling 4 or other panels are suitably attached. An angle iron 5 is attached, along one of its flanges, to the

iron frame of the door section, so that the 55 other flange projects lengthwise of the door, beyond the edge of the frame. A door mounted in this manner, in order not to run too loosely, would have to have the free edge of the flange 6 of the angle iron 5 60 close to the vertical guide bar 2. That, however, is objectionable, for in case of fire when the door expands, the angle iron 5 would be jammed against the guide 2 and the door would buckle and the parts would become 65 locked, and such a construction is not permissible. For that reason the door is made of such dimensions that the free edge of the flange 6 of the angle iron 5 is some distance from the vertical guide bar 2, say from one- 70 half to three-quarters of an inch.

The bearing piece 7 is formed by cutting a slot 8 in the flange 6 of the angle iron 5, and bending the material between the slot and one edge of the flange outward at one 75 end, at which end the slot extends to the edge of the flange, the material bent outward constituting the bearing piece, which bearing piece is thus united with the flange 6 at its lower end, and at its upper end is 80 entirely detached from the flange. The cut or slot made is curved at its upper end as shown at 8^a, so that the member 7 can easily be forced out and when necessary forced inward, into the recess formed in the 85 flange. The free end of the bearing piece projects about one-half an inch, more or less, beyond the free edge of the flange 6 and is close to the guide rail 2, as the door moves up and downward. 90

As the bearing pieces 7 on the opposite ends of the door are close to their respective guide rails 2 and project beyond the free edges of the flanges 6 for about a half an inch, more or less, the outer edges of the 95 flanges 6 are so far away from the guide rails 2, that said flanges 6 can move laterally under the effect of heat about a half an inch, more or less, before they will contact with the guide rails.

If the doors expand under the effect of heat, the pressure produced by said expansion, forces the bearing pieces 7 into the recesses formed by making slots 8 and bending outward the pieces 7. I thus have a 105 bearing piece which guides the door properly without danger of binding in case of fire.

The bearing piece 7, which is free at its upper end, is very apt to be bent laterally during transportation of the door, or while erecting the same, or even while in use, and to prevent such bending, I secure washer plates 9 to the opposite surfaces of the bearing piece 7, at the free end of the same, which washer plates extend to or beyond the outer edges of the upper end of the bearing piece 7 and laps over the solid part of the flange 6, as shown at 12, thus preventing any lateral movement of the bearing piece 7.

The bearing piece is also apt to be bent inward and toward the end edge of the door and thereby cause looseness in the door, through frequent manipulation of the door, or carelessness in mounting and is also apt to be forced, by successive hammering and wear and tear, back into the recess from which it was originally bent. To prevent this I provide the washer resting against the inner surface of the flange 6, with diverging curved arms 11 which bear against that flange of the angle iron 5 which is attached directly to the frame of the door and at the same time they rest on the adjacent surface of the flange 6. These arms have convex inner edges, facing the base of the angle iron 5, and their outer edges are concave, so that the arms are thinnest where they emerge from the washer disk 9. These arms are of sufficient strength to hold the bearing piece 7 projected beyond the edge of the flange 6 during ordinary usage and to prevent inward displacement of such bearing piece during transportation and while erecting the doors.

When, in case of fire, the doors become heated and expand, the arms 11 also become heated, more or less, and can easily bend at their thinnest point, which is at their juncture with the washer disk 9 and can diverge still more under the pressure produced by the heat, between the bearing piece and the guide bar 2, thus permitting the bearing piece 7 to be forced into its recess.

So as to prevent the parts from catching on the arms 11, they are beveled at their concave edges toward the flange 6, as shown at 14.

Normally the upper end of the bearing piece extends outward beyond the end of the flange 6 and is close to or in contact with the guide piece 2. The divergent arms 11 afford sufficient resistance against accidentally forcing the bearing piece into its recess 8.

When the door becomes heated and the bearing piece 7 is subjected to the pressure produced by such heat, the bearing piece can be forced into its recess 8 and the arms 11 can bend under pressure on the bearing piece. As the door expands, the edge of the flange 6 of the angle iron moves toward the guide 2 and in the same proportion, the

bearing piece 7 is forced back into the recess 8, so at no time, whether the door is cold or hot, is there any danger of the door binding or buckling.

Having described my invention what I claim as new and desire to secure by Letters Patent is:

1. The combination with a vertically sliding door and a guide therefor of bearing members projecting beyond the extreme side edges of the door and capable of displacement toward the door, and divergent extensions rigidly mounted upon said bearing members respectively and extending into substantial engagement with the edge of the door frame whereby said bearing members are normally held in their projected position and are permitted under excessive stresses to have movement toward each of the doors.

2. The combination with a vertically movable door and a guide rail for the same, of a plate on the side edge of the door, part of said plate being bent outward to form a bearing member which at its outer end projects beyond the edge of the plate, and washers on the free end of said bearing member, overlapping part of the web from which the bearing member is cut, substantially as set forth.

3. The combination with a vertically movable door and a guide rail for the same, of a plate on the side edge of the door, part of said plate being bent outward to form a bearing member which at its outer end projects beyond the edge of the plate, and washers on the free end of said bearing member, overlapping part of the web from which the bearing member is cut and wings projecting from one of said washer plates to a plate on the door, substantially as set forth.

4. The combination with a vertically movable door and a guide rail for the same, of a plate on the side edge of the door, part of said plate being bent outward to form a bearing member which at its outer end projects beyond the edge of the plate, and washers on the free end of said bearing member, overlapping part of the web from which the bearing member is cut, diverging wings extending from said washer plate to a bearing plate on the door, which wings have convex inner edges and concave outer edges, substantially as set forth.

5. The combination with a vertically movable door and a guide rail for the same, of a plate on the side edge of the door, part of said plate being bent outward to form a bearing member which at its outer end projects beyond the edge of the plate, and washers on the free end of said bearing member, overlapping part of the web from which the bearing member is cut, diverging wings extending from said washer plate to a bearing plate on the door, which wings have convex

inner edges and concave outer edges, the wings being beveled at the convex edges, substantially as set forth.

6. The combination with a vertically movable door and a guide rail for the same, of a plate on the side edge of the door, part of said plate being bent outward to form a bearing member which at its outer end projects beyond the edge of the plate, and washers on the free end of said bearing member, overlapping part of the web from which the bearing member is cut, diverging wings extending from said washer plate to a bearing plate on the door, which wings have convex inner edges and concave outer edges, said wings containing less metal in cross section, adjacent to the washer plates, than in the remaining part of the length, substantially as set forth.

20 7. The combination with a vertically sliding door, of a guide rail for the same, an

angle secured to the end of the door, one flange of said angle projecting from the door in the direction toward the guide rail, a bearing member cut out from the projecting 25 flange and bent from the same in the direction toward the guide, a washer plate on the free end of said member, which washer plate overlaps part of the flange above mentioned, arms projecting from the said washer plate 30 to and in contact with that flange of the angle iron which is at right angles to the flange from which the said member is cut, substantially as set forth.

Signed at New York city, borough of 35 Manhattan, in the county of New York and State of New York, this 8th day of December, A. D. 1915.

BENJAMIN WEXLER.
